UNITED STATES PATENT OFFICE.

ARTHUR L. HALLIDAY, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 12,427, dated August 23, 1881.

Application filed July 14, 1881. Term of patent 3½ years.

To all whom it may concern:

Be it known that I, ARTHUR L. HALLIDAY, of Yonkers, in the county of Westchester and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The figure B is a stripe containing the figure *g*, a band ornamented with a series of broken parallel lines, also containing the figure *e*, a band ornamented with a series of two rows of flower-like figures, each row fitting into the interstices of the other.

The figure A is a stripe containing the figure *h*, composed of two rectangular loops supported on a sort of rectangular pedestal, and with a background of parallel lines running along the stripe A. In the opening between the figures *h*, which are set at intervals, comes the figure *i*, a bunch of circular flowers with leaves projecting around them.

The figure *a* is a background containing a pattern of angular figures.

The figure C consists of two large open circular flowers with surrounding leaves and sprays, one of these sprays, *f*, somewhat resembling a branch of coral.

The figure *d* resembles a pillar with two rectangular loops, one on each side, and having set on its end the figure *i*, already described.

The figure D consists of a center of widely-open rose-like flowers surrounded by pointed

leaves and leafy branches, and having projecting from it the flowering branch *e*, consisting of flowers set on slender stems. This branch *e* extends over a background, *b*, having the appearance of braided or interlaced work. These various figures are repeated at intervals in the stripe A.

I claim—

1. The design for carpets, consisting of the figure *g*, substantially as shown. 45
2. The design for carpets, consisting of the figure *e*, substantially as shown.
